CLAIM

The ornamental design for a tibial baseplate with fixation members, as shown and described.

DESCRIPTION

FIG. 1 is a front perspective view of a tibial baseplate with fixation members according to my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is top plan view thereof;

FIG. 7 is a bottom plan view thereof;

FIG. 8 is a rear bottom perspective view thereof; and,

FIG. 9 is a right side bottom perspective view thereof.

The broken lines illustrate unclaimed environmental structure and form no part of the claimed design.
